PETROLEUM OIL REFINING PROCESS

Byron M. Vanderbilt and Anthony H. Gleason,
Westfield, N. J., assignors to Standard Oil Development Company, a corporation of Delaware

No Drawing. Application July 28, 1949,
Serial No. 107,383

7 Claims. (Cl. 196—24)

1

This invention relates to an improved process for refining mineral oils. The process is directed to the removal of gum forming substances, to the sweetening of the oils treated, and to the color improvement of these oils. In accordance with this invention treating agents consisting of finely divided metallic sodium and a secondary or tertiary alcohol are utilized as refining agents.

At the present time a great many refining processes are known for improving the quality of mineral oils. These processes are generally directed to improving one or more characteristics of the oil so as to produce superior oils. For example, in the refining of gasolines, it is frequently desirable, or necessary, to improve the odor of the gasoline by "sweetening" the gasoline so as to remove malodorous mercaptans, or so as to convert them to compounds which do not have an objectionable odor. Again refining processes are used to increase the resistance of the oil to oxidation, decreasing the tendency of the oil to form objectionable gum deposits in storage and transit. The process of this invention is, therefore, directed to this general field in which petroleum oils are refined in a manner to improve the characteristics of these oils.

While the process of this invention is of general application to mineral oils, or petroleum oils generally, it will be described with particular reference to the refining of cracked gasolines as this is presently contemplated to be the most important application of this process. As a refining process for gasolines, a major objective of this process is to provide a stable and a sweet gasoline. In the past it has been the practice to achieve this by two treating processes, i. e. treating with sulfuric acid and sodium plumbite. A further object of this invention is to decrease the oxidation instability of gasolines. As will be apparent from the ensuing description, these and other objectives are attained by the single step refining process described herein.

In its broadest scope this invention concerns the treatment of a mineral oil with sodium, potassium, or lithium in combination with a suitable activator. The activator may consist of a mono or polyhydric alcohol although it is presently felt that monohydric alcohols are more suitable. A particularly effective refining agent (or agents) consists of fine particles of sodium together with a minor proportion of a secondary or tertiary alcohol. In the description which follows, reference will particularly be made to this specific refining agent although it is to be understood that potassium or lithium may be used in place of sodium and further that other types of activators may be employed.

2

As indicated the novel refining agent of this invention consists of a major proportion of finely divided sodium and a minor proportion of a secondary or tertiary alcohol. It is believed that the alcohol probably reacts with sodium to form a sodium alcoholate. If this is true the refining agent may be said to be a sodium alcoholate formed in the presence of an excess of sodium so that free sodium is present with the alcoholate. In this connection, however, it is significant that the desired refining results cannot be obtained by utilization of either sodium alone or sodium alcoholate alone. Again, the most desirable refining results can not be obtained by forming the sodium-alcohol reaction products, believed to be primarily the alcoholate, in the absence of hydrocarbons. While the exact nature of this effect is not yet thoroughly understood, it appears that a more desirable refining agent is obtained when the alcoholate is formed in the presence of suitable hydrocarbons, such as those present in cracked gasolines. A further point of criticality concerning the refining agent of this invention is the use of suitable alcohols. Thus primary alcohols are not suitable, while secondary and tertiary alcohols appear to be generally suitable. Furthermore, it is desirable that the secondary, or tertiary alcohol used have less than about 7 carbon atoms since the reaction products formed with a greater number of carbon atoms are sufficiently soluble to necessitate distillation of the oil after treating. Hence the preferred alcohols are secondary alcohols having from 3 to 6 carbon atoms, and tertiary alcohols having from 4 to 6 carbon atoms. Of these the preferred alcohols are iso-propyl alcohol, and secondary and tertiary butyl alcohols.

The sodium utilized in this novel refining process is preferably supplied as a fine dispersion of sodium in a suitable vehicle such as a hydrocarbon oil. Such a dispersion may be obtained by adding sodium to the vehicle and by then heating the mixture of sodium and the vehicle to a temperature above the melting point of the sodium. Upon then agitating the melted sodium, and the vehicle, a fine dispersion of the sodium may be obtained. The vehicle may consist of virtually any hydrocarbon oil but is preferably a high boiling gasoline fraction substantially free of olefinic materials. It is desirable to utilize a high speed agitator, a homogenizer, a colloid mill or similar means for thoroughly dispersing the molten sodium in the vehicle. In this connection it has been found critical that the sodium have a particle size of less than about 50 microns in diameter. Further it has been found highly desirable that the sodium have diameters not

greater than about 30 microns and preferably below an average of 10 microns.

This dispersion of sodium in a hydrocarbon oil can then be added to the oil to be refined in combination with suitable quantities of a suitable alcohol. Thereafter the desired refining may be accomplished by heating the mineral oil in the presence of the indicated refining agent for a period of about 10 minutes to two hours, at a pressure suitable to hold the mineral oil in liquid phase, and at temperatures of 70° to 160° C., or higher. At the conclusion of the refining period the mixture is cooled, if necessary, to a temperature below about 100° F. and the spent refining agent, together with any unreacted sodium and constituents removed from the oil may be settled from the refined oil in the form of a sludge. The remaining oil will be found to be suitably refined without necessity for re-running or other treating steps. In order to more clearly disclose the nature of this invention, consideration will be directed to typical examples embodying and defining the process of this invention.

EXAMPLE I

A crude gasoline boiling in the range of 170° to 400° F. which was obtained by the thermal cracking of a reduced crude oil was contacted for one hour, at 70° C., with 1% by weight of finely divided sodium. The sodium was added to the gasoline in the form of a dispersion in straight run kerosene, in weight proportions of about 1 to 1, and having a particle diameter of about 30 microns. During the hour of contact, internal agitation was provided to thoroughly mix the sodium and gasoline. After the treating period the mixture was cooled to room temperature, a sludge and unreacted sodium was removed from the gasoline by filtration. The treated gasoline comprising the filtrate was then tested by a variety of tests as indicated in Table I. For comparative purposes, in Table I, the results of these same tests are given on a control sample of the gasoline employed.

Table I

	ASTM Break-down ¹	Peroxide No. ²	Copper Dish Gum ³	Doctor Test ⁴	Diazonium Deposit Factor ⁵
Control Sample.....	260	0.6	14	Did not pass.	41
Example I.....	180	-----	17.8	Passes.....	36
Example II.....	470	-----	7.8	do.....	27
Example III.....	800	0.1	4.9	do.....	18

¹ Indicates oxidation stability in minutes according to ASTM test D 525-46.

² Indicates the active oxygen content of the gasoline.

³ Indicates gum content in mg./100 cc. obtained by evaporating the gasoline at 210° F. in a copper dish.

⁴ Indicates presence or absence of mercaptans by utilization of sodium plumbite solution and a trace of free sulfur. If no color change occurs mercaptans are absent and the gasoline is said to "pass."

⁵ Indicates engine cleanliness characteristics of gasoline. This test utilizes the coupling reaction which takes place between diazotized p-nitro aniline and certain unsaturated compounds (which cause engine fouling) to form a colored compound. Intensity of color formed after a given time interval is taken as an index of the deposit forming compounds present. In running the test the fraction of the sample boiling over 275° F. and purified by treatment with dilute acid and alkali and steam distillation to 3% bottoms is used. A known quantity of this fraction is added to a solution of p-nitro-aniline diazonium fluoroborate ($\text{NO}_2\text{C}_6\text{H}_4\text{N}=\text{NBF}_4$) in acetone and the optical density measured at intervals in a Hellige-Diller emission photometer. The optical density is plotted against time and the value after 20 minutes read from the curve. The optical density multiplied by the ratio of the fraction boiling over 275° F. to the whole sample gives the diazonium deposit factor.

It will be noted from Table I, that the sodium treatment of the gasoline did not markedly improve the quality of the gasoline. The ASTM

break-down test indicated that the sodium treatment was actually ineffective in increasing the oxidation stability of the gasoline which is borne out also by the Copper Dish gum test which indicated that a greater amount of gum was formed after the gasoline had been subjected to the sodium treatment. The sodium treatment was effective in causing the gasoline to pass the Doctor test, but was only slightly effective in increasing the quality of the gasoline as indicated by the diazonium deposit factor.

EXAMPLE II

The gasoline treated in Example I, was treated in the same manner except that 5% of the stoichiometric amount of isopropyl alcohol required to react with the sodium was added to the gasoline prior to the addition of the finely divided sodium. The isopropyl alcohol employed was of 99% purity. The results of this test are again indicated in Table I, identified as Example II. It will be noted that as indicated by these data, the ASTM break-down test and the Copper Dish gum test indicated a material improvement in the oxidation characteristics of the gasoline, while the Doctor test showed that mercaptans were removed, and the diazonium deposit factor of the gasoline indicated marked improvement in the engine cleanliness characteristics of the gasoline. A comparison of the results obtained by the treating steps of Example II, as compared to Example I, indicates a marked advantage for the process in which the isopropyl alcohol was present.

EXAMPLE III

The experiment performed in Example II was repeated, except that after one-half of the one-hour contact time an additional 5% of the stoichiometric quantity of isopropyl alcohol was added. In this example, therefore, 10% of the molar quantity of the isopropyl alcohol, based on the sodium was utilized. Again, the results of this test are indicated in Table I, identified as Example III. It will be noted from these data that the improvement in the gasoline characteristics, as indicated by each of the tests, was materially better than in either of the previous treating runs. Again, therefore, in comparing Examples I, II and III, the importance of having a significant amount of alcohol present is borne out, indicating that a molar proportion of about 10% of alcohol based on total sodium is desirable.

Further experiments were conducted, particularly directed to an evaluation of suitable alcohols for use in the process of this invention. These experiments will be indicated below as Examples IV to IX inclusive, the results of which are summarized in Table II appended herewith. In these tests the gasoline treated was obtained by the thermal cracking of a reduced crude oil stock and had a boiling range of about 170° F. to 400° F. The gasoline was characterized by the inspections given in Table II, showing the ASTM break-down time, Copper Dish gum number; peroxide number; the Doctor test; the total sulfur, and the diazonium deposit factor of the gasoline. In each of the treating Examples V to IX, 10 molar percent of various alcohols were used based on the quantity of sodium employed. The amount of sodium used was 0.75% based on the gasoline treated and it was added in the form of a dispersion in a fraction of virgin crude oil having a boiling point of 360° to 480° F. The

sodium particles had an average diameter of about 30 microns, and were present in the dispersion in a weight percent of about 50%. In each of the tests conducted, the alcohol was mixed in the gasoline prior to the addition of the sodium dispersion. After a contact time of one hour, at a temperature of 90° C., while employing mild agitation, the treated gasoline was separated from the sludge and unreacted sodium by filtration at room temperature. Results of the test are indicated in Table II.

Table II

Ex. No.	Alcohol Used	ASTM Break- down	Copper Dish Gum	Peroxi- de No.	Doctor Test	Total Sulfur
IV	Control	215	13	0.8	DNP Passes	0.108
IV	None	340	4.5	0.2	do	0.093
V	Methyl	305	3	0.2	do	0.091
VI	Ethyl	240	15.5	0.2	do	0.105
VII	Isopropyl	625	7.5	0.1	do	0.096
VIII	Sec-Butyl	720	2.5	0.1	do	0.090
IX	n-Butyl	290	19.5	0.3	do	0.090

As shown by Example IV, identified in Table II, when using sodium alone as the refining agent in the absence of an alcohol, a relatively small improvement of the gasoline was obtained in regard to oxidation stability as indicated by the ASTM break-down test. A further characteristic of Example IV, was the poor sodium dispersion which was maintained during the contacting, resulting in the formation of large sodium agglomerates at the end of the treating period.

Example V, utilizing methyl alcohol together with sodium, was also characterized by poor sodium dispersion, and again did not result in materially improving the ASTM break-down characteristics of the gasoline.

Example VI, utilizing ethyl alcohol, indicated that an excellent sodium dispersion could be obtained using the ethyl alcohol, but as indicated by the data, did not result in materially improving the quality of the gasoline. Thus, as shown by the ASTM break-down data, the Copper Dish gum test, and the total sulfur content, the refining of the gasoline with sodium in the presence of ethyl alcohol did not substantially improve the gasoline.

Examples VII and VIII, utilizing isopropyl alcohol and secondary butyl alcohol respectively, resulted in the formation of excellent sodium dispersions, and as indicated by the data, served to materially improve each of the characteristics of the gasoline as determined by the tests indicated.

Finally, Example IX of Table II, utilizing normal butyl alcohol, even though a good dispersion was obtained, again demonstrated that the refining results utilizing a primary alcohol are not good even though a secondary alcohol of like molecular weight was quite effective.

The data of Table II substantiate the conclusion that when no alcohol is employed, a poor sodium-sludge dispersion is obtained which is also the case when using methyl alcohol. Further, the primary alcohols tested, methyl, ethyl, and normal butyl alcohol appear to offer no advantage in sodium refining over the case in which no alcohol whatever is used. This result is particularly surprising in view of the fact that ethyl alcohol results in the formation of an excellent sodium dispersion. Finally the data demonstrate that the secondary alcohols, such as isopropyl alcohol and secondary butyl alcohol, are highly

effective in enhancing the defining effects of sodium.

Restating the conclusions drawn from the data of Table II, it is particularly significant that the function of the alcohol employed is not simply to provide a better sodium dispersion. The data indicate the possibility that the sodium and alcohol may enter into some complex with olefins, or other hydrocarbons present to form a more active refining catalyst. This conclusion is strengthened by the data obtained in Examples X and XI, following.

EXAMPLE X

400 grams of a gasoline obtained in a thermal cracking operation, having a boiling range of about 170 to 400° F., was treated with 3.6 grams of sodium (0.9% by weight) and 1.53 grams of finely ground sodium isopropylate (equivalent to 0.1% of combined sodium). The sodium isopropylate was prepared by adding metallic sodium to an excess of pure isopropyl alcohol and isolating, drying the grinding to a fine powder the alcoholate obtained. Thus, 10% of the total sodium present was present in the form of the sodium isopropylate. The dispersion of sodium particles had diameters of 2 to 5 microns and the alcoholate passed through a 40-mesh screen. The mixture with gasoline was heated with agitation for one hour at 90° C. after which the gasoline was separated by filtration. The results of this test are indicated in Table III below.

Table III

	ASTM Break- down Test	Percent Sulfur	Diazo- nium Deposit Factor	Peroxide No.	Copper Gum No.
Untreated Gasoline	190	146	55	1.4	264
Example X	12	64	6	94	94
Example XI	365	127	39	4	10

EXAMPLE XI

For comparative purposes with Example X, a refining operation was conducted utilizing the identical conditions as in Example X, except that the isopropyl alcohol was first added to the gasoline to be refined prior to the addition of the sodium, that is, the sodium isopropylate was not extraneously formed in this example, but was formed in situ (if at all) in the presence of the gasoline to be refined. The results of this experiment are also indicated in Table III. It will be noted from a comparison of Examples X and XI, that materially better refining results were obtained according to the procedure of Example XI, in which the sodium alcoholate was formed in situ rather than being preformed. Thus the deposit factor, peroxide number and copper gum number of the gasoline refined according to the steps of Example XI are materially better than those obtained by the procedure of Example X.

As a still further example of this invention a cracked thermal naphtha was treated with a dispersion of sodium together with tertiary butyl alcohol. In this example, 400 grams of the cracked thermal naphtha were mixed with 1.3 grams of tertiary butyl alcohol and 4 grams of sodium introduced in the form of a sodium dispersion in kerosene containing 45% sodium by weight. These quantities provided a total sodium content of 1% along with 10 molar percent of the alcohol based on the sodium. Agitation was maintained for one hour at a temperature of

90° C. The sludge, and unreacted sodium were removed by filtration, after cooling below 100° F., and the treated gasoline filtrate was compared with the untreated stock according to the tests indicated in Table IV. It will be observed in this table that the refining of the gasoline with the sodium, in the presence of the tertiary butyl alcohol resulted in a substantial improvement of the gasoline quality as indicated by each of the tests.

Table IV

	ASTM Break-down Test	Copper Dish Gum	Peroxide No.	Doctor Test	Deposit Factor
No Treat	160	27	1.4	DNP	56
Example XII	900	1.5	0.3	Passes	18.5

EXAMPLE XIII

A one percent solution of thiophene was prepared in pure para xylene. Four hundred grams of this solution was contacted for one hour at 90° C. with 3.3 grams of colloidally dispersed sodium having an average diameter of five microns. After the contact period the sludge was removed by filtering at room temperature and the filtrate analyzed for sulfur content.

EXAMPLE XIV

Example XIII was repeated but modified in that 1.1 cc. of isopropyl alcohol (10 mole percent based on the sodium) was added to thiophene solution before adding the sodium dispersion.

EXAMPLE XV

Example XIV was repeated but run at a temperature of 120° C. for one hour.

Indicated in Table V are the sulfur contents of the untreated and treated xylene solutions.

	Percent sulfur
Untreated	0.248
Example XIII	0.250
Example XIV	0.134
Example XV	0.103

It may be noted that when no alcohol was used with the sodium, none of the thiophene was removed. When isopropyl alcohol was employed with the sodium, a substantial part of the sulfur was removed when treating at 90° C. and a still larger amount removed when treating at 120° C. A still larger percentage of the thiophene sulfur was removed on treating at temperatures of 160° and higher.

EXAMPLE XVI

When normal propyl alcohol was used in a run similar to Examples V-IX (Table II) the following results were obtained on the treated stock:

	ASTM Break-down	Copper Dish	Peroxide No.	Doctor Test	Total Sulfur
Control	235 160	63 264	0.4 1.4	Passes DNP	0.111 0.146

It may be noted that while this example utilized a different control stock than that for Examples V-IX, the results are in line.

EXAMPLE XVII

A sample of naphtha from catalytic cracking having an ASTM boiling range of 325-437° F.

was treated in various ways for the primary purpose of lowering its high sulfur content of 0.385%. Heavy catalytic cracked stocks are high in sulfur which is difficult to lower even a small degree by the usual methods of refining such as sulfuric acid treating. Samples were treated as follows:

(a) Treated with one percent of finely divided sodium 3-5 microns) along with 10 mole percent of isopropyl alcohol for one hour at 160° C.

(b) As (a) but run for two hours at 160° C.

(c) As (b) but using ten mole percent of tertiary butyl alcohol instead of the isopropyl alcohol.

(d) No metallic sodium was used but finely divided sodium isopropylate, equivalent to one percent sodium, was employed for one hour at 160° C.

Sulfur contents of the untreated and treated stocks were as follows:

	Percent sulfur
Untreated	0.385
Example XVII (a)	0.093
Example XVII (b)	0.075
Example XVII (c)	0.072
Example XVII (d)	0.396

It may be observed that the isopropylate is entirely ineffective in lowering the sulfur content of the cracked naphtha whereas the sodium-alcohol combinations are quite effective as formerly indicated by the examples utilizing thermally cracked gasoline.

In accordance with these principles, therefore, the improved refining process of this invention comprises the introduction of a fine dispersion of sodium to the oil to be refined, containing from 5 to 25 molar percent (based on sodium) of a secondary or tertiary alcohol having from 3 to 6 carbon atoms. The oil to be refined, the sodium, and the alcohol are then agitated for a period of about one-half to two hours, at a temperature above about 70° C., and thereafter the refined oil is separated from the sludge which has formed. Thus the refined oil may be recovered by utilization of a settling zone operative to permit the sludge to settle from the refined oil. Alternatively, a centrifuge, a filter, or other means may be used to separate the sludge from the refined oil. Oil entrained with, or adsorbed on the sludge may if desired be recovered by heating the sludge sufficiently to drive out the adsorbed oil. Thereafter the sludge may be quenched with steam or water to convert all reacted and unreacted sodium to sodium hydroxide.

What is claimed is:

1. A process for improving the oxidation stability and engine cleanliness characteristics of a cracked gasoline comprising the steps of separately adding to the gasoline about 1% by weight of a metal selected from the class consisting of sodium, potassium, and lithium and about 5 to 25 molar percent of an alcohol based on the amount of the said metal, said alcohol being selected from the group consisting of secondary and tertiary alcohols of less than 7 carbon atoms, mixing the gasoline containing the metal and the alcohol for a period of ten minutes to two hours at a temperature above 70° C., and thereafter separating the gasoline from sedimentitious material.

2. The process of claim 1 in which the alcohol is selected from the class consisting of isopropyl alcohol, secondary butyl alcohol, and tertiary butyl alcohol.

9

3. The process of claim 1 in which the cracked gasoline is a thermally cracked gasoline.

4. The process of claim 1 in which the cracked gasoline is a catalytically cracked gasoline.

5. The process of claim 1 in which the said metal is added as a dispersion in a hydrocarbon oil having particle sizes of less than about 50 microns in diameter.

6. A process for improving the oxidation stability and for sweetening a cracked gasoline comprising the steps of contacting said gasoline with an agent consisting of finely dispersed sodium and an alcohol selected from the group consisting of secondary and tertiary alcohols having less than 7 carbon atoms to provide a proportion of about 1% by weight of sodium and about 5 to 25 molar percent of the alcohol based on the amount of sodium, said contacting being carried out at a temperature above 70° C., and thereafter separating the treated gasoline from sedimentous material.

7. A process for improving the oxidation stability of a petroleum oil fraction in which the said oil is agitated with a minor quantity of sodium having a particular size less than 50 microns together with an alcohol selected from

10

the group consisting of secondary and tertiary alcohols having less than 7 carbon atoms, said agitation being conducted at a temperature above 70° C. and said alcohol being present in the proportion of 5 to 25 molar percent based on the sodium employed.
